[57] CLAIM

The ornamental design for a blood chemistry sensor assembly, as shown.

DESCRIPTION

FIG. 1 is a top plan view of a blood chemistry sensor assembly embodying our new design;

FIG. 2 is a rear elevational view thereof;

FIG. 3 is a left side elevational view thereof;

FIG. 4 is a right side elevational view thereof;

FIG. 5 is a bottom plan view thereof;

FIG. 6 is a front elevational view thereof; and,

FIG. 7 is a top, front perspective view thereof.

FIG. 2.

FIG. 3.

FIG. 1.

FIG. 4.

FIG. 5.

FIG. 6.
